UNITED STATES PATENT OFFICE.

CHARLES A. MAXFIELD, OF NEW YORK, N. Y., ASSIGNOR TO JACOB WALLACE, TRUSTEE, OF SAME PLACE.

APPARATUS FOR TREATING TEXTILE FABRICS WITH WATERPROOFING, &c.

SPECIFICATION forming part of Letters Patent No. 328,958, dated October 27, 1885.

Application filed May 23, 1885. Serial No. 166,498. (No model.)

To all whom it may concern:

Be it known that I, CHARLES A. MAXFIELD, a citizen of the United States, and a resident of New York, in the county of New York and State of New York, have invented certain new and useful Improvements in Apparatus for Treating Textile Fabrics, Paper, &c., with Waterproofing, Coloring, or Glossing Substances, of which the following is a specification.

My present invention relates to apparatus for coating or saturating textile fabrics, paper, leather, and similar substances with wax, or with any desirable waterproofing, coloring, or glossing substance. It is adapted to the use of the natural wax known as "ozoocerite," paraffine, gums, india-rubber, and analogous strengthening, preserving, and waterproofing materials; and is also designed for use in applying coloring or glossing materials to the surface of paper and fabrics of various descriptions and grades.

My object is to produce an apparatus which is simple in construction and effective in operation, and one adapted to apply the waterproofing, strengthening, glossing, or coloring substance as a coating simply to the surface (one or both) of the material operated upon, or to completely saturate the said material.

My invention consists in the organization herein shown and described, and in certain details of construction. The subject-matter for which I desire protection in this instance is pointed out in the claims at the end of this description.

In the accompanying drawings, which form a part of this description, and in which like letters indicate like features, Figure 1 illustrates a vertical central longitudinal section of a machine organized according to my invention. Fig. 2 is a plan view of the same machine. Fig. 3 is a cross-section through the line *y y*, Fig. 1. Fig. 4 is a cross-section through the line *x x*, Fig. 1. Fig. 5 is an enlarged detached view of the plate *E* shown in Fig. 3, which forms a part of the wax-receptacle hereinafter described. Fig. 6 is an enlarged view of the elements forming the receptacle, said view being a longitudinal vertical section showing one of the side plates in elevation. Fig. 7 is a plan view of one of

the side plates; and Fig. 8 is a detail view of a brake mechanism, shown attached in Fig. 2 to the shaft of the paper-delivery reel.

Referring to the drawings, *A* indicates a frame, which may be of cast-iron or of any other suitable material. Mounted upon one end of this frame, which is constructed of dimensions adapted for the purpose in view, is the paper-delivery reel *B*, and at the opposite end of the machine is located the paper-receiving reel *C*. Both of these reels are provided with shafts *B'* and *C'*, respectively, which have bearings in the frame of the machine in the usual manner. The upper longitudinal bars, *a*, of the frame *A* support the castings, which constitute the receptacle and the distributor.

The receptacle, as shown, is composed of two iron castings, *D* *D'* *E*, forming the front and rear walls, and that wall *D* of said receptacle nearer the delivery-reel is so shaped on its under side as to provide a smooth surface for the paper to travel under and insure close contact between paper and casting while the paper is passing under the receptacle, as shown. The inner surface of the casting *D* is vertical and smooth, except near its lower end, where it is provided with a projection constructed to form one element of a dovetail connection. A pipe, *d*, is located within this casting *D*, as shown, and at the top of said casting is a flat piece of metal, *d'*, of the requisite length, secured rigidly thereto, and provided with screw-bolts, whereby the said casting *D* may be adjusted longitudinally of the frame in order to increase or diminish the distance between the castings *D* and *D'*. The casting *D'* is similarly constructed, except that it has no projection on its inner face, as is the case with the casting *D*. It is preferably curved on its outer surface and flat on its under surface, and it has secured to its inner wall, by set-screws *e*, the blade *E*, or this blade may be cast as part of it. The holes to receive these set-screws *e* are elongated, in order to permit the blade to be adjusted vertically, so as to enable said blade to be accurately placed in position upon the casting. On the lower face of the blade *E* is a projection forming one element of a dovetail joint. The blade *E* may project upward

above the frame of the machine. The casting D' is also provided with a pipe, d, and with the flat piece of metal d² at its top, having set-screws which permit the adjustment of said 5 casting lengthwise of the machine, in order to bring it nearer to or farther from the casting D.

F represents the two-part side plates, which are shown enlarged in Figs. 6 and 7. These plates overlap each other and are adjustable 10 in length by means of the set-screw f. The outer end of each of these plates is provided with a slot formed so as to receive the projection on the inner wall of the casting D and blade E, respectively, thereby completing the 15 dovetail joint between the respective castings and the side plates. There are two sets of the plates F, one at each end of the receptacle, and they are of sufficient height to form the end walls of said receptacle, and while 20 their upper edges are straight their lower edges incline slightly from the casting D to the beveled edge of the blade E, so as to insure an easy movement of the paper beneath the receptacle. The blade E, forming the rear 25 wall, may be made without the casting D', and heated in another manner.

Immediately above the receptacle is a tank, G, which is supplied with the coating or saturating material, liquefied and kept hot by any 30 suitable means. At the bottom of this tank is a series of discharge-cocks, g, having projections from their plugs connecting with a rod, g', whereby all the cocks may be opened at the same time and in the same degree, and 35 thus insure the supply of the liquid to the receptacle evenly over the surface of so much of the material operated upon as for the moment forms the bottom of this receptacle.

From this description it is plain that my 40 receptacle has no bottom; that its front and rear walls are formed by the castings D and D' E, which may be adjusted toward or from each other, so as to increase or decrease the space between said walls; that its side walls 45 are formed by the two sets of side plates, F, which are detachably connected to the castings D D' E, and which may be adjusted in length by the set-screws shown, so as to accommodate themselves to the adjustments of 50 the castings D D' E. The side plates are also adapted to be moved transverse of the machine toward or from each other, in order to increase or diminish the width of the receptacle according to width of the paper or fabric 55 operated upon. The longitudinal adjustment of the receptacle is for the purpose of increasing or diminishing the surface of the liquefied substance in contact with the material operated upon.

60 Projecting from the edges of the plates F are lugs f', which receive set-screws f², so that when the plates F are properly adjusted they may be locked in position.

H represents a pivoted bar secured upon 65 the frame of the machine by a central pivot and extending transverse of the frame. This bar is located just in advance of the delivery-

reel B, and is adapted to hold the paper above the lower surface of the casting D, so as to insure proper contact between the paper and the lower surface of said casting. The fact 70 that the bar H is pivoted also insures the passage of the paper beneath the receptacle in an unruffled manner, as any irregularities in the paper are compensated for by the automatic 7 adjustment of said bar.

At a suitable position on the frame is secured the casting I, which is constructed the same as casting D', having an interior pipe, d, and flat and curved walls. To the flat face of this casting is secured in a detachable and adjustable manner the blade J, whose lower end is beveled. The casting I is adjustable longitudinally of the machine by the set-screws passing through the plate at its top. The 85 function of blade J is to further insure the even distribution of the material upon the paper or fabric operated upon.

Between the castings D' and I is arranged the bar K, pivoted to the frame and capable 90 of being thrown in and out of operation when desired. The function of this bar K is to keep the paper properly in contact with the blades E and J.

The tension on the delivery-reel B is regulated by the device shown in Fig. 8. The application of this device to the shaft of the delivery-reel is shown in Fig. 2. This tension device consists of a metal strap, K', secured at l and passed over the shaft B', the free end 100 of the strap being connected to the spring m, which spring is connected with a bar, n, the latter being secured near the base of the machine and provided with means for depressing or elevating it, so as to increase or decrease the 105 strain on the spring, and thereby easily regulate the tension of the delivery-reel. The pipes d forming parts of the castings D, D', and I, are connected by means of suitable couplings with steam-supply pipes L. Hot air or 110 hot water may be used instead of steam for heating the castings forming the receptacle and the casting I, and, for convenience, the pipe of casting D' may be connected permanently with the pipe of casting I, in which 115 case the longitudinal adjustment of these two castings will not be independent of each other, and the relative distance between the castings of the receptacle will be regulated by the longitudinal adjustment of the casting D. 120

In operation the paper or other material to be treated is conducted from the delivery-reel B over the pivoted bar H, under the bottom of the casting D, and beneath the open bottom of the receptacle and blade E, from which point 125 it is carried over the pivoted bar K, under the blade J of casting I, to the receiving-reel C. In this position the paper or material to be operated upon forms the bottom of the said receptacle. The parts being adjusted as contemplated, the liquefied material, when permitted, will flow from tank G through the stop-cocks g upon the paper or fabric forming the bottom of the receptacle D D' E. The depth 130

of the liquefied substance is of course to be regulated according to the quality of paper or other material operated upon, and according as to whether the paper is to be saturated or

merely coated. In operating with very thin paper but a small depth of liquid would be allowed to pass into the receptacle, and this would be the practice in operating upon heavy paper where the object is to coat and not saturate. If the liquid is to be struck through the paper so as to saturate it, a heavier body of liquid would be allowed to enter the receptacle D D' E. The liquid in the receptacle D D' E is kept at a predetermined temperature by regulating the degree of heat permitted to affect the castings forming the walls of said receptacle.

The revolution of the reel C draws the paper M from the reel B over the equalizing pivoted tension-bar H, under the wax-receptacle, and under the blade J, after passing which latter point it is sufficiently treated to be wound upon the receiving-reel C.

The blade E prevents any undue quantity of the liquefied material from adhering to the paper or other material being treated, and such as remains upon the paper or other material treated is further equalized upon its surface during the act of passing under the blade J.

In practice I may dispense with the front wall, D, of the receptacle, leaving this receptacle to be formed of the rear wall, D' E, and attached side walls, F, with the incline of the material operated upon, the walls F being made with an incline to conform.

Having thus described my invention, what I claim as new, and desire to secure by Letters Patent, is—

1. In an apparatus of the character herein described, a receptacle for the liquefied substance to be applied to the material operated upon, consisting of front and rear walls secured to the frame of the apparatus and provided with adjustable side walls, said structure being open at the bottom, so that the material to be operated upon, when passing beneath the same, is in direct contact with the liquid, substantially as set forth.

2. A receptacle for the liquefied substance to be applied to the material operated upon, consisting of front and rear walls provided with heating-pipes and secured to the frame of the apparatus, and adjustable side walls, said structure having an open bottom, substantially as set forth.

3. A receptacle for the liquefied substance to be applied to the material operated upon, consisting of front and rear walls adjustable longitudinally upon the frame of the apparatus, so that the distance between these walls may be regulated, and end plates which

are adjustable in length, and also capable of adjustment transverse of the machine, the bottom of said structure being open, substantially as set forth.

4. A receptacle for the liquefied substance to be applied to the material operated upon, consisting of the wall D' E and end plates, F, the material operated upon forming in operation the bottom of the said receptacle, substantially as set forth.

5. The walls D D' and end plates, F F, the wall D' having a blade, E, substantially as set forth.

6. The walls D D', the former provided with a projection on its lower interior face, and the latter, D', having secured to its interior face the blade E, upon whose lower face is a projecting rib, combined with the plates F F, the latter being adjustably and detachably connected to the walls D D', substantially as set forth.

7. The open-bottom receptacle D D' F, provided with the blade E, by which the proper application of the liquefied substance to the material operated upon is regulated, substantially as set forth.

8. In combination with the receptacle D D' E F, the pivoted equalizing tension-bar H, substantially as set forth.

9. In combination with the receptacle D D' E F, the supplemental distributing device, consisting of the casting I, having a heating-pipe, and blade J, substantially as set forth.

10. The receptacle D D' E F, combined with the distributing device I J and bar K, substantially as set forth.

11. The combination of the receptacle D D' E F and equalizing tension-bar H with the bar K and distributing device I J, substantially as set forth.

12. In an apparatus of the character described, the delivery-reel B, combined with a tension device upon its shaft, and the equalizing pivoted tension-bar H, substantially as set forth.

13. An apparatus organized for coating or saturating textile fabrics, paper, leather, and similar substances with strengthening, preserving, or coloring matter, comprising the following elements: delivery and receiving reels, an open-bottom receptacle for the substance to be applied, an equalizing pivoted tension-bar, H, a bar, K, and a distributing device, I J, substantially as shown and described.

Signed at New York, in the county of New York and State of New York, this 19th day of May, A. D. 1885.

CHARLES A. MAXFIELD.
